SAFETY FLAG

John B. Baker, P.O. Box 368,
Issaquah, Wash. 98027

Filed June 7, 1974, Ser. No. 477,198

Term of patent 7 years

Int. Cl. D10—06

U.S. Cl. D10—109

FIG. 4

FIG. 5

FIG. 6

FIGS. 1 and 2 are respectively left and right side elevational views of a safety flag showing my new design;

FIG. 3 is a front view of the flag mount, the flag being omitted for convenience of illustration;

FIGS. 4 and 5 are respectively top and bottom plan views of the flag mount, the flag being omitted for purposes of disclosure; and

FIG. 6 is a side elevational view on a greatly reduced scale, the bicycle being shown in broken lines for illustrative purposes only.

The cross-hatching on the flag is partially shown for convenience of illustration, it being understood that the cross-hatching is uniformly continuous over the flag. The cross-hatching is omitted from the flag in FIG. 6 for convenience of illustration because of the small scale.

I claim:

The ornamental design of a safety flag, substantially as shown and described.
